13 Claims. (Cl. 198—16)

Our invention relates to new and useful improvements in an escalator and more particularly to a moving stairway suitable for conveying passengers.

A principal object of our invention is in the provision in an apparatus of this character of an arrangement of parts so constructed as to afford easy installment of the escalator utilizing a minimum amount of space.

Another object of our invention is in the provision in an apparatus of this character of a novel arrangement of parts so constructed as to afford ready adjustment between varying floor levels.

Yet another object of our invention is in the provision in an apparatus of this character of a new and novel drive mechanism.

A further important object of our invention is in the provision in an apparatus of this character of a step wheel transferring means between running and reversing tracks.

An additional object of our invention is in the provision of an apparatus of this character which employs upper and lower sections which are pre-fabricated and which may be simply joined together upon installation to achieve a complete single standardized unit.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a schematic side elevational view of our improved escalator;

Fig. 2 is a fragmentary detailed perspective view of one side of one end of the track construction;

Fig. 3 is a fragmentary detailed perspective view similar to Fig. 2 but showing certain parts thereof in an adjusted position;

Fig. 4 is a perspective view of the reversing track adjusting member;

Fig. 5 is a fragmentary detailed sectional view taken on line 5—5 on Fig. 2;

Fig. 6 is a fragmentary detailed view of the wheel arrangement for the endless step train associated with our apparatus;

Fig. 7 is a fragmentary perspective view of the step train utilized in our invention;

Fig. 8 is a fragmentary detailed sectional view of the track and wheel arrangement embodied in our invention;

Fig. 9 is a fragmentary side elevational view of the wheel and track transferring arrangement of our invention;

Fig. 10 is a fragmentary detailed view of a modified form of wheel arrangements for the step train;

Fig. 11 is a side elevational schematic view of the drive mechanism employed in our escalator;

Fig. 12 is a fragmentary detailed view showing the driving connection between a portion of a step and the drive mechanism;

2

Fig. 13 is a detailed sectional view taken on line 13—13 of Fig. 12; and

Fig. 14 is a perspective view of our improved landing treadway.

5 In prior art practice the conveyor systems have required the operational functions of sprocket wheels at each level adjacent the track ends for driving and reversing the direction of the step train of such escalators. The drive mechanisms included an endless chain associated with such sprocket wheels. In our present invention these elements and their functions have been omitted.

10 Our invention pertains to an escalator for use in a semi-private establishment such as a home, multi-level factory or business office, motel or hotel. However, this 15 particular statement of the purpose of our invention is not intended to limit the use of our invention in any manner.

15 Referring to the drawings, particularly Fig. 1, there is shown in a schematic view an escalator for conveying passengers between two floor levels which are represented as landings 10 and 11. Our escalator as it extends between landings 10 and 11 comprises two sections 12 and 13. Each section includes as a part thereof an inclined upper and lower track 14 and 15 respectively. Each section has a curved track terminal end 16 and 17 respectively. As each terminal end is identical, and as each side wall structure of each end is identical we will describe but one.

20 Referring to Figs. 2 and 3 we see that each end section 20 comprises a bottom wall 18 which supports a vertical side wall 19. A detachable retaining member 20 is secured by means of bolts 21 or the like to the inner face of the side wall 19. A base member 22 is supported by the bottom wall 18 and has one edge thereof in facial 25 abutment with the side wall 19. This base member has its inner end portion 23 formed to provide a portion of an inclined track 24. Slidably carried between the base member 22 and the retaining member 20 is a terminal end plate 25. This plate 25 includes a U-shaped retaining wall 26 and a center wall 27. One edge of the center wall 27 is arcuated so as to conform to the arcuation of the U-shaped retaining wall 26. The plate 25 is provided with an arcuated groove which cooperates with the U-shaped retaining wall 26 to form a reversing track 27. The U-shaped retaining wall 26 cooperates with the 30 arcuated edge of the center wall 27 to provide an inner reversing track 28.

25 Carried by the side wall 19 and in spaced relation to the retaining wall 20 is a track forming bar 29. This track forming bar is removably connected to the side 30 wall 19 by bolts 30 or the like. The forward end 31 of the bar 29 is tapered vertically out of the longitudinal plane thereof.

35 A like bottom track forming bar 32 is carried by the side wall 19 in vertical spaced alignment with respect to the upper track forming bar 29. The lower track forming bar 32 has its one end 33 inclined out of its longitudinal plane as seen in Figs. 2 and 3.

40 A center wall section 34 is disposed between the upper and lower track forming bars 29 and 32 and cooperates therewith to form tracks 28a and 28b therebetween. The upper track forming bar 29 cooperates with the retaining wall 26 to form therebetween a track 27a. The lower track forming bar 32 cooperates with the base member 22 to provide therebetween a lower track 27b. One end 45 35 of the center wall section 34 is inclined with respect to its longitudinal plane as seen in Fig. 2.

45 From the foregoing description of parts it is readily seen that the upper tracks 27a and 28a converge toward each other and form the upper track 14 at a point beyond the inclined end 31 of the upper track forming bar 29. Likewise tracks 27b and 28b converge and form

lower track 15 at a point beyond the end portion 33 of the lower track-forming bar 32.

To the tracks 27 and 28 formed in the terminal end plate 25, we provide track rails for extending therebetween. These track rails 36, 37, 38, 40 and 41 are fixedly carried by the terminal end plate 25 and extend in a horizontal direction with respect thereto. The free ends of the rails 36, 37, 38, 40 and 41 are slidably contained in suitable grooves formed in the upper and lower track forming bars 29 and 32 and the center wall section 34. Referring to Fig. 5, we show the rails 36, 37 and 38 slidably projected into grooves 36', 37' and 38'.

It is readily apparent that the terminal end plate 25 together with all of its track forming elements is slidably positioned between the base member 22 and the retaining member 20 in order to make the tracks 27a, 27b and 28a, 28b continuous with respect to tracks 27 and 28.

The method employed by us for slidably connecting the terminal end plate 25 together with the retaining wall 26 and center wall 27 is as follows: The retaining wall 26 and the center wall 27 are formed as an integral unit and are in turn fixedly connected to the terminal end plate 25 by two spaced apart parallel rails 42 and 43. In order to permit slidable adjustment of these parts horizontally with respect to the bottom wall 18 and the side wall 19 the rails 42 and 43 are adapted to frictionally fit into grooves 44 and 45 formed in the inner face of the side wall 19, see Figs. 2, 3 and 4.

The opposite side walls of our escalator as exemplified by side wall 19 are held in spaced parallel relation by spacer bars 46 and 47. It is noted that spacer bar 46 is fixedly connected to the center wall 27 and therefore is adjustably carried thereby. It should also be noted that the tracks are adapted to encircle such spacer bars so that such bars will in no way interfere with the operation of our escalator.

Referring to Fig. 7 we show a perspective fragmentary view of our proposed step train 48. Such step train consists of a step 49 having side walls 50 and 51 together with a center partition 52. A riser 53 is fixedly attached to the leading edge of the side walls 50 and 51 and partition 52. A step tread 53 is removably carried by the top edge of such walls and partition. The side walls 50, 51 and partition 52 are substantially triangular in shape and have a forward wheel supporting shaft 54 journaled therethrough adjacent one angle of the triangular shaped walls and partition. A second wheel bearing shaft 55 is journaled through such walls and partition at a second angle thereof. The shaft 54 rotatably supports guide wheels 56 and 57. These guide wheels 56 and 57 are positioned exterior of the side walls 50 and 51, immediately adjacent the outer sides thereof. The shaft 55 rotatably supports running wheels 58 and 59. These wheels 58 and 59 are exterior of and spaced from the outer faces of the side walls 50 and 51. From the foregoing description it is readily apparent that the guide wheels 56 and 57 are inwardly off-set with respect to the running wheels 58 and 59.

The running wheels 58 and 59 are connected to a plurality of like running wheels 58' and 59' by means of two spaced apart link arms 60 and 61. The running wheels 58, 59 and 58', 59' together with their linkage comprising the arms 60 and 61 are a part of an endless running wheel arrangement.

Fixedly carried by the shaft 54 and in facial abutment with the inner face of the side walls 50 and 51 are depending arms 62 and 63. Laterally supported by the arms 62 and 63 and extending outwardly with respect thereto is a roller bearing 64 and 65. It should be noted that these roller bearings 64 and 65 are in vertical alignment with the guide wheels 56 and 57 rotatably supported by the shaft 54. The purpose and function of the roller bearings 64 and 65 will be hereinafter made apparent.

From the foregoing description it is clear that the portion of the step train that is traveling through the tracks

14 and 15 will position each step 49 thereof in its normal raised step relation. In order to reverse the direction of movement of the step train at each of the ends 16 and 17, the relationship between each step of the step train must be changed. In order to accomplish this it is required that the running wheels 58, 59 and 58', 59', move in one track in this instance tracks 27, 27a and 27b, while the guide wheels 56 and 57 are transferred and guided into tracks 28, 28a and 28b. In order to accomplish this result we provide the following structure:

For the purpose of illustration let us assume that the upper track 14 has the step train moving in an upward direction therethrough and the lower track 15 has the step train returning in a downward direction. As each step of the step train approaches the terminal end 17 the roller bearings 64 and 65 will be caused to engage a track switching means 66. This track switching means 66 comprises an arcuated member 67 fixedly mounted to the center wall section 34 at the end of the lower track 15 as viewed in Fig. 2. The switching member 66 has its lower edge 68 in horizontal alignment with the upper face of the track 15 and the upper face of the track 28b. The switch member 66 is of a length so that its one end portion extends beyond the tapered end 33 of the lower track forming bar 32. The running wheels 58 and 59 of each of the step units of the step train will by the force of gravity move down through track 15 pass beneath the inclined edge 33 of the lower track forming bar 32 and move into track 27b. As the guide wheels 56 and 57 approach the end of the track 15 the roller bearings 64 and 65 will engage the upper leading edge 69 of the switching member 66 and will prevent the guide wheels from passing into the lower track 27b. The roller bearings 64 and 65 will maintain contact with the switching member 66 until the guide wheels 56 and 57 have been guided into track 28b, see Fig. 9.

We contemplate in the operation of our escalator to employ a drive mechanism that will permit the direction of the step train to be controlled so that it may move in either direction. This is to say that that portion of the step train that is traveling through the track 14 may be utilized to carry passengers in either direction i.e. up or down. In the event that the step train is traveling in a downward direction through track 14 as each step approaches the lower end of such track, it again requires a switching operation on the guide wheels and running wheels of each step. The upper track switching means is shown in Fig. 8. As each step moves downwardly through the track 14 the guide wheels 56 and 57 become the leading wheels for each step. As they approach the terminal end 17 the roller bearings 64 and 65 will engage a switch member 70. This switch member 70 is positioned so as to present an upper edge that is in surface alignment with the bottom edge of the track 14. In Fig. 8 it is seen that the roller bearing 65 has engaged the switch member 70 and has caused the guide wheel 57 to pass beneath the inclined end 31 of the upper track forming bar 29 so as to pass into track 28a. The track 14 at this point is comprised of two sections having different depths. As the running wheel 59 was laterally off-set with respect to the guide wheel 57 it is caused to travel in the deepest portion 71 of track 14 which deepest portion 71 will guide the wheel 59 into track 27a. Thus we have provided a switching means for the step train when it encircles the terminal ends in either direction.

In our improved escalator each step 49 of the step train has positive driving connection with a driving means. This positive driving connection for each of the steps 49 consists of a plurality of spaced apart depending gear teeth 72 formed as an integral part of the center partition 52 of each step 49.

Between the side walls of the upper section 12 of our escalator is carried a chain drive mechanism. The supporting structure for such chain drive is not disclosed

herein and it may take the form of any convenient structure necessary for such purpose.

Referring to Fig. 11 we show our driving mechanism as including an electric reversible motor 73. This reversible motor 73 in turn drives a driving gear 74. This driving gear 74 has operable connection with an endless chain 75. This chain is adapted to pass around terminal gear wheels 76 and 77. The chain 75 is guided about its circuitous path by upper and lower guide tracks 78 and 79. Each of these guide tracks 78 and 79 has their end portions reversely inclined as at 80, 81 and 82, 83. The guide tracks 78 and 79 are so positioned so as to present the chain 75 into a position whereby the gear teeth 72 of each step 79 can engage such chain. Such an arrangement is clearly shown in Fig. 12.

In order to insure proper drive connection between the gear teeth 72 and the chain 75 we form the gear teeth 72 of such a length that they will project into the chain 75. In order to allow such projection the outer faces of each of the tracks 78 and 79 are formed to provide spaced apart slide rails 84 and 85. It is upon these slide rails 84 and 85 that the chain 75 actually travels over. Such construction is shown in Fig. 13 and by this novel arrangement of parts it is clearly shown that the gear teeth 72 may project through the links of the chain 75.

As previously stated it is our intention that the step train of our escalator be capable of traveling in either direction. In order to control the operation of our escalator we provide a treadway 86 which is adapted to be positioned at each of the landings 10 and 11. This treadway 86 internally provides switch means (not shown) for starting and stopping the electric reversible motor 73 of the drive mechanism. Certain of these switches are connected in series and are positioned beneath yieldable switch actuators 87 and 88. Other of these switches are connected in parallel and are closed by like yieldable actuators 89 and 90. The arrangement of these switches results in the following operation. Let us say a person approaches the landing 10 and wishes to start the escalator so that he may travel down the escalator to landing 11. The person will step on the treadway 86 and with each foot step upon the yieldable switch actuators 87 and 88 thus closing a suitable electric circuit for the reversible motor 73. When the person reaches landing 11 he will step upon the treadway 86 at that point and with either foot actuate either of the yieldable switch actuators 89 and 90 so as to disrupt the electric circuit for the reversible motor 73. It is readily apparent that the switches contained in the step treadway 86 on the landing 11 would cause the reversible motor 73 to run in an opposite direction thereby reversing the travel of the step train of our escalator.

As a safety feature each treadway 86 is provided with a slidible edge plate 91 which upon slidible movement in one direction will disrupt the electric circuit to the reversible motor 73. Thus if an object or a person riding the step train does not step off at the approaching landing the plate 91 will be actuated by engagement of the object or the person's foot thereagainst to stop the running of the escalator. The treadway 86 together with its switches and safety plate is fully described in our co-pending application Serial No. 829,610.

Attention is directed to Fig. 10 in which we show a modified means for connecting the running wheels 58 and 58' to the trailing shaft 55 of each of the steps 49. In such modified form the shaft 55 extends outwardly from the side walls of the step 49 and passes through a hollow sleeve 92 and extends through the link arms 60 and 61 equally distant with respect to the ends of the link arms 60 and 61 and wheels 58 and 58'. As seen in Figs. 8 and 9 and as can be expected there is a slight clearance between confronting surfaces of the tracks 27b, 28b and the wheels of the step train. In order to reduce to the minimum the amount of play between the wheels and the track faces when the weight of a person or object is placed on the treadle portion of each step 49 it is desirous to

equally distribute the weight between two adjoining wheels. Such will be the result from the use of this modified form.

In order to insure against any possible lateral vibrations of the step 49 between the side walls of the escalator we provide on each of the outer surfaces of the side walls 50 and 51 adjacent the free angle corner thereof a nylon guide 93. This nylon guide 93 will engage the side walls of the escalator with a minimum amount of friction and wear.

Each of the two sections 12 and 13 of our escalator are pre-fabricated as standard complementary sections. When placed between floor levels the end 94 of the lower section 13 can be cut off so as to accommodate installation between levels having various distances therebetween. The number of steps in the step train can be regulated by adjusting the terminal end plates 25 horizontally with respect to the remaining end portions 16 and 17 of the escalator.

After the sections 12 and 13 have been installed and the tracks 14 and 15 longitudinally aligned, the retaining member 20 carried by each of the side walls is removed. The upper track forming bar 29 carried by each of the side walls is removed. The step train may then be placed so that the running wheels 58 of each step may be placed on the remaining portion 71 of track 27a and the guide wheels 56 may be placed in the track 28a and the continuous train then set into the track system until a continuous step train has been formed in the track system in the escalator. The horizontal adjustment of each of the terminal end plates 25 carried by each of the side walls of the supporting structure is adjusted to compensate for any differences in the required number of full steps for the escalator. In other words when installing the sections 12 and 13 between a specific distance of floor levels there might result a surplus or deficit in the form of a percentage of a full step width. The adjustment of the terminal end plates 25 may be readily made to increase or decrease the surplus or deficit.

As is evident from the foregoing description of our improved escalator, the driving means for the step train is located in the upper section 12 between the tracks 14 and 15. It therefore requires that there be a simplified means of access to such driving mechanism for service and necessary repairs if any. This is accomplished through a step construction which permits the removal of the riser and tread portion of a step without the disconnecting of any step from the step train or displacement of the wheels from their respective tracks. This construction of the step can be accomplished in many ways and no specific structure need be specifically shown therefor.

While we have illustrated and described the preferred form of construction for carrying our invention into effect, this is capable of variation and modification without departing from the spirit of the invention. We therefore do not wish to be limited to the precise details of construction set forth, but desire to avail ourselves of such variations and modifications as come within the scope of the appended claims.

Having thus described our invention, what we claim as new and desire to protect by Letters Patent is:

1. An escalator comprising complementary upper and lower sections each having spaced apart parallelly extending side walls with the side walls of each section having one end thereof formed to provide horizontally extending end portions, said side walls having formed therein upper and lower inclined tracks with said tracks of each section being longitudinally aligned when said sections are connected together in complementary relationship, said inclined tracks terminating into a plurality of vertically aligned horizontally extending transfer tracks carried by said end portions of said side walls, curved track means slidably mounted on said end portions of said side walls for adjustably connecting corre-

spending ends of said plurality of transfer tracks together in a continuous reversing pattern, means for slidably mounting said curved track means to said end portions of said side walls for horizontal adjustment thereof with respect to said plurality of transfer tracks, and horizontally extending track extension means fixedly carried by said curved track means cooperating with said plurality of transfer tracks for maintaining a continuous endless track during slidable horizontal adjustment of said curved track means with respect to said plurality of transfer tracks.

2. An escalator as defined by claim 1 wherein the means for slidably mounting said curved track means to said end portions of said side walls comprises spaced apart guide rails carried by said curved track means and slidably projecting into spaced apart vertically aligned horizontally extending grooves formed in the confronting faces of said end portions of said side walls.

3. An escalator as defined in claim 1 wherein the track extension means fixedly carried by the said curved track means comprising laterally extending track bars having certain edges thereof in horizontal alignment with said plurality of transfer tracks, said track bars movable horizontally into corresponding grooves formed in said plurality of transfer tracks when said curved track means is horizontally adjusted with respect thereto.

4. An escalator as defined by claim 1 wherein the means for slidably mounting said curved track means to said end portions of said side walls comprises spaced apart guide rails carried by said curved track means and slidably projecting into spaced apart vertically aligned horizontally extending grooves formed in the confronting faces of said end portions of said side walls, and wherein the track extension means fixedly carried by the said curved track means comprising laterally extending track bars having certain edges thereof in horizontal alignment with said plurality of transfer tracks, said track bars movable horizontally into corresponding grooves formed in said plurality of transfer tracks when said curved track means is horizontally adjusted with respect thereto.

5. An escalator comprising a circulatory endless track having inclined horizontal and curved sections through which an endless wheeled step train is adapted to be moved, means for horizontally adjusting the curved sections of said track relative to the horizontal track section without interrupting the continuity of said circulatory endless track; said horizontal sections provided with a plurality of vertically aligned track paths for guiding certain wheels of each step of said wheeled step train so as to change the relationship of each step with respect to the next succeeding step during its travel through said horizontal track sections, means for guiding said certain wheels of each step of said wheeled step train into a selected track path of said plurality of track paths, wheel guiding means carried by each of said steps for guiding other wheels of each of said steps into a selective track path of said plurality of track paths, and driving means periodically operatively connected to each step of said step train for moving said step train through said endless track.

6. An escalator as defined by claim 5 in which said means for guiding certain wheels of each step into a selected track path includes a switch member mounted adjacent confronting ends of said inclined track section and said horizontal track sections.

7. An escalator as defined by claim 5 wherein said wheel guiding means on each step for guiding said other wheels of each of said step includes a depending roller bearing laterally extending from each step adapted to engage said guiding means and direct the movement of said certain wheels of each step into a selected track path as it passes from said inclined track section to said horizontal track section.

8. An escalator as defined by claim 5 in which said driving means includes a reversible endless link chain rotated about spaced apart gear wheels carried by said inclined track section, and an electric reversible motor for driving said link chain.

9. An escalator comprising a circulatory endless track having inclined horizontal and curved sections through which an endless wheeled step train is adapted to be moved, means for horizontally adjusting the curved sections of said track relative to the horizontal track section, said horizontal sections provided with a plurality of vertically aligned track paths for guiding certain wheels of each step of said wheeled step train so as to change the relationship of each step with respect to the next succeeding step during its travel through said horizontal track sections, means for guiding said certain wheels of each step of said wheeled step train into a selected track path of said plurality of track paths, a driving means for said endless wheeled step train, said driving means having operative connection with each step of said step train for moving the same through said endless track, means carried adjacent said inclined track sections for positioning said driving means in operative connection with each step of said step train for moving the same through the circulatory endless track, and means provided by each step for cooperating with said driving means for operatively connecting each step periodically to said driving means.

10. An escalator as defined by claim 9 wherein the said means on each step cooperating with said driving means includes a plurality of gear teeth.

11. An escalator as defined by claim 9 in which said driving means includes a reversible endless link chain rotated about spaced apart gear wheels carried by said inclined track section, and an electric reversible motor for driving said link chain.

12. An escalator as defined by claim 9 including track extension means fixedly carried by said curved track section adapted to cooperate with said plurality of track paths provided by said horizontal track section during horizontal adjustment of said curved track section with respect to said horizontal track section for maintaining a continuous endless track for said wheeled step train.

13. An escalator as defined by claim 12 wherein the track extension means fixedly carried by said curved track section comprises laterally extending track bars having certain edges thereof in horizontal alignment with said plurality of track paths, said track bars movable horizontally into corresponding grooves formed in said horizontal track sections adjacent said plurality of track paths when said curved track section is horizontally adjusted with respect thereto.
